DESIGN FOR A NEGLIGEE

Ethel Eaton Stricker, New York, N. Y.

Application October 8, 1937, Serial No. 72,055

Term of patent 3½ years

To all whom it may concern:

Be it known that I, Ethel Eaton Stricker, a citizen of the United States of America, residing in New York city, in the Borough of Manhattan, county and State of New York, have invented a new, original, and ornamental Design for a Negligee, of which the following is a specification, reference being had to the accompanying drawing, forming part thereof, wherein,

The figure is a front view of a negligee showing my new design.

The rear portion of the negligee is conventional.

The characteristic feature of my design resides in the sleeve members of the negligee as shown.

I claim:

The ornamental design for a negligee, substantially as shown and described.

ETHEL EATON STRICKER.
